UNITED STATES PATENT OFFICE.

WILLIAM STREETER, OF ROCHESTER, NEW YORK, ASSIGNOR TO SARGENT & GREENLEAF, OF SAME PLACE.

PERMUTATION-LOCK.

SPECIFICATION forming part of Letters Patent No. 269,136, dated December 12, 1882.

Application filed August 22, 1882. (Model.)

To all whom it may concern:

Be it known that I, WILLIAM STREETER, of Rochester, Monroe county, New York, have invented a certain new and useful Improvement in Locks; and I do hereby declare that the following is a full, clear, and exact description of the same, reference being had to the accompanying drawings, in which—

Figure 1 is a horizontal section through the lock, and the door to which it is attached, in the line of the spindle. Fig. 2 is an elevation of the lock looking from the rear and showing the same on an enlarged scale. Fig. 3 is an elevation of the dial looking from the inner side. Fig. 4 is a plan, and Fig. 5 a cross-section, of one of the tumblers on an enlarged scale. Fig. 6 is a perspective view of one of the flies.

My improvement relates to combination-locks, and is of that kind where a sleeve runs through the door and receives the spindle, and in which the lock is attached or clamped to the door by means of the sleeve and connecting parts without using screws for screwing the lock to the door, as formerly practiced.

The invention consists, first, in combining with a sleeve having a solid dial-ring which rests against the outside of the door, a lock having leveling-screws which bear against the inner side of the door, by which means the parts may be brought in firm contact with and clamped to the door, and be at the same time leveled and evened to produce a firm bearing.

It also consists in the construction of the tubular sleeve and dial made in one piece or rigidly secured together, with a disk on the inner face of the dial which bears against the door, and a screw-thread on the inner end of the sleeve which screws directly into the lock-case, thereby avoiding the attachments ordinarily employed at the inner end for attaching the sleeve to the lock, and also avoiding screw-threads or other connections at the outer end where the sleeve attaches to the dial.

It furthermore consists in the peculiar construction of the fly, having a right-angled lug or tang which enters a corresponding slot in the center-piece of the tumbler in line with the driving-pin of the next tumbler, all as hereinafter described.

In the drawings, A shows the door to which

the lock is attached, a being the outside plate and a' the inside plate.

B is the lock, being in itself of ordinary construction.

55

C C are the tumblers.

D is the spindle.

E is the dial, and E' is the knob by which the lock is operated.

G is a hollow tubular sleeve which extends 60 through the door and holds the spindle. At its inner end it has a screw-thread, b, which screws into the back plate of the lock and is the only connection by which the lock is held to the door. At the outer end the dial-ring 65 H forms a solid attachment to the sleeve, being either made integral with it or rigidly attached by rivets, screws, or other means.

c is a disk forming a shoulder at the end of the sleeve, this disk abutting against the outer 70 plate and resting flush with the outer edges of the dial-ring H. By this means a solid head is made, which rests against the outer plate of the door, and the sleeve has simply to be inserted through the door and be drawn up 75 on the inside to secure it in place, differing in this respect from those devices where a screw-thread is cut on the outer end of the sleeve and a nut screwed thereon outside of the door. By this means, also, a flange or head is avoided 80 on the inner end of the sleeve for the attachment of the lock and the use of small screws for attaching the lock to the flange is avoided, thus strengthening the connection and avoiding difficulty in drawing the lock up to place against 85 the inside of the door.

I I I I are four leveling-screws—one in each corner of the lock—screwing through the back plate of the lock and resting against the back plate of the door, as shown in Fig. 1. These 90 screws are slotted at their inner ends, so that they can be driven by a screw-driver; or they may be provided with square heads to be driven by a wrench. By turning these screws up more less the sleeve is drawn up in the door, bringing 95 the solid disk c and the edges of the dial-ring H against the outside of the door, while the lock itself is firmly stiffened and fastened against the inside of the door by the pressure of the screws. The lock is keyed upon the end of 100 the sleeve, as shown at d, Fig. 2, and when in place more or less of slackness is left be-

tween the lock and the door. The screws take up this slackness and tighten the parts when forced up to place. Another important advantage of the screws consists in their ability to level or adapt the lock on one side and the disk and dial-ring on the other side to the surfaces against which they rest.

If there is any unevenness or failure of any part of the lock or dial-ring to form a bearing the difficulty is remedied by turning up any one of the screws more than the others to take up the slack, thus forming a true and solid bearing throughout.

One or more of the leveling-screws I have 15 projecting point, *f*, which rests in a socket *g*, bored in the back plate of the door, as shown in Fig. 1. This prevents the lock from being turned around out of position.

Each of the tumblers *C* consists of an outer 20 rim and a center-piece, as usual.

K is a fly, which rests and turns freely on the stud *h* upon which the tumblers rest. The fly consists of a thin ring, having a projecting tongue, *i*, against which the driving-25 pin of the next tumbler strikes, its object being to allow the pin a full rotation to set the gatings of the tumblers. This fly is in common use and well known. The tongue, as it is operated by the driving-pin, strikes stops 30 on opposite sides, which limit its motion. Heretofore the stops have been either inside or outside of the track of the driving-pin in the groove *l*, which is objectionable, as it causes cramping on the fly itself, which is a thin ring 35 and liable to bind upon the stud on which it turns, and when force is applied is liable to break the tongue. To obviate these difficulties I construct the tongue *i* with a right-angled lug, *i'*, Fig. 6, and cut a slot, *m*, through 40 the center-piece of the tumbler, in which slot the lug rests and turns, the ends of the slot forming the stops to the tongue. The slot is cut through the tumbler coincident with the groove *l*, and therefore the lug lies directly 45 in the path of the driving-pin and not outside or inside of it, and by this means the action of the driving-pin is direct, and all strain and tendency to springing or cramping is avoided and much greater strength is secured.

The driving-pin *p* is attached to the center piece of the tumbler diametrically opposite to the tongue *i* and on the reverse face, as shown in Fig. 5. When the tumblers are turned the 55 bearings of the several driving-pins against the tongues alternate or come on opposite sides.

Heretofore, so far as I am aware, in all locks where a fly is used the driving-pin is on the back of the center-piece in line with and coincident with the fly. In such case, when the tumblers are turned, the engagement of the driving-pins with the flies is all on one side and in line, which causes strain and makes the tumblers bind on the stud on which they 60 turn. By locating the driving-pins diametrically opposite the flies, as in this invention, when the wheels are turned the driving-pins alternate in their engagement with the flies, thus balancing the strain and obviating bind- 65 ing of the wheels on the stud.

Having described my invention, what I claim as new, and desire to secure by Letters Patent, is—

1. The combination of the tubular sleeve 75 having the dial-ring attached fast at its outer end and provided with a screw-thread at its inner end, the lock-case attached to the inner end of the sleeve, and the leveling-screws in the back plate of the lock-case bearing against the 80 inner face of the door for tightening and leveling the lock and dial against the door, as herein shown and described.

2. In a combination-lock, the tubular spindle *G*, constructed with a disk, *c*, at its outer 85 end resting flush with the outer edges of the dial-ring, a dial-ring formed solid with the sleeve and with a screw-thread on the inner end of the sleeve for connecting with the lock, as herein shown and described.

3. The fly *K*, provided with the tongue *i* and offset-lug *i'*, in combination with the center-piece of the tumbler provided with the slot *m*, the slot lying in the groove *l*, and the lug extending through the slot directly in the track 95 of the driving-pin of the next tumbler, as shown and described, and for the purpose specified.

4. In combination with the fly *K*, provided with the tongue *i* and offset-lug *i'*, the driving-pin *p*, attached to the center-piece of the tumbler diametrically opposite the tongue and on the reverse side of the tumbler, as herein shown and described.

In witness whereof I have hereunto signed 105 my name in the presence of two subscribing witnesses.

WILLIAM STREETER.
